BACK BRUSH

Bernice P. Garzelloni, Covina, Calif.

Application November 19, 1953, Serial No. 393,077

2 Claims. (Cl. 15—160)

This invention relates to back brushes, and has as an object the provision of a brush which can be used to reach ordinarily inaccessible areas of the body.

A further object is to provide a construction which eliminates the possibility of injuring the skin by contact with exposed hard parts of the brush. An allied object is to provide means for spreading substances over the body.

A feature of the invention resides in a multi-element brush which is surrounded by bristles on all sides and has flexible straps extending from opposite ends of the brush. The structure of the brush and means for attachment of the straps are so constructed and disposed that all hard parts are held away from contact with the body when the brush is used. A related optional feature resides in a cover for the brush by means of which substances may be spread over the body.

A brush with flexible straps attached is not new in itself. However, prior devices of this nature have been so constructed that bristles could be placed on but one side of the brush assembly, and the hard supporting structure of the brush could therefore contact and scratch the body. This resulted in an inconvenient device. The instant invention avoids these difficulties, and provides a brush which may be used without any precautions, or cares as to its position.

These and other features of the invention will be fully understood from the following detailed description and the accompanying drawings, of which:

Fig. 1 is a plan view of a brush according to the invention;

Fig. 2 is a detail, in plan view, of a means for attachment of a strap to the brush structure;

Fig. 3 is a cross-section taken along line 3—3 of Fig. 2;

Fig. 4 is a detail, in plan view, of a means for attaching an optional form of strap to the brush; and

Fig. 5 is an isometric view particularly illustrating a cover for the brush.

In the drawings, Fig. 1 shows a brush 10 according to the invention with three individual brush elements 11, 12, 13, disposed in a single plane. These brush elements are of conventional manufacture, wherein the bristles are held between two twisted wires, and have bristles on all sides thereof. The ends of outer elements 11 and 13 are bent so as to meet the ends of brush 12 at right angles.

Two flexible straps 14, 15 which may be of cloth or plastic have a hole 25 near one end, and a loop 16, 17 for a handhold at the other. One strap is then fixed to each end of element 12 by inserting the end of the brush element into the hole 25. The brush structure itself is then assembled by means of a clamp 18, which has three tubular arms 19, 20, 21. One of these clamps and one flexible strap will thus be provided at each end of the brush. As best shown in Fig. 3, arms 19 and 21, which are to receive brush elements 11 and 13 respectively, are formed by folding a metal plate so as to create the tubes 19 and 21, and then crimping the ends of the plate so as to form wings 22, 23. Tubular arm 20, in the center, is

2

conveniently formed by stamping channels into opposite sides of the plate, and a hole 23a at the middle before the plate is folded. This hole will be in the edge of the fold when the plate is folded. All tubular arms are then open at both ends to receive the ends of the brush elements.

The ends of the brushes are next inserted into the tubular arms as shown, and are held therein by dimpling each arm of the clamp as at 24. Each strap is then folded back over the clamp and sewed as at 26. The clamp, and all structure not protected by bristles are thus covered by the flexible strap.

Fig. 4 shows an alternate and simpler form of strap, and one which is particularly useful as a replacement when the original strap is worn out. While this strap may also be made of cloth, it is conveniently made of some fusible plastic material. This optional strap is a strip 27 having a pair of split tabs 28, 29 on one end. These tabs are bent around the arms of the clamp, one on each side of the center arm 20, and are fused or sewed to the back side of the strip.

Fig. 5 illustrates a smooth cover 30 for this brush by means of which unguents and the like may be spread over the skin. The cover comprises a top surface member 31, which may preferably be made of chamois or some soft cloth, a side member 32 stitched to the top member, and an elastic band 33 around the lower edge of the side member. Holes 34 at each end permit straps to be pulled through the cover without interfering with the side member. The elastic band holds the cover in place over the bristles. When it is desired to spread substances over the body, this cover is simply stretched over the brush, and the substance applied to the cover. This cover thus covers at least half of the bristles.

In use, one strap is held in each hand, and the brush is pulled back and forth. This brush is suited for reaching parts of the body which are inaccessible with conventional wooden-handled brushes. This is particularly advantageous to crippled and obese people. With the cover on, a person may give himself a complete alcohol rub, or spread lotions or powders, as preferred. The convenient construction provides a brush which is also useful without the straps, for the straps do not interfere with the brush, as does a wooden handle, for example. The construction is light and flexible, and is well suited for traveling.

The unique construction provides a brush with bristles on all sides. It will be noted that all metal parts, or parts which might scratch or abrade the skin, are held away from the skin, either by the bristles or by the covering action of the strap. There is thus no danger of scratching the skin by placing the wrong side of the brush next to the body, since all sides are alike. The user thus need take no care as to the orientation of the brush faces.

My invention is not limited to the embodiment shown in the drawings, and described in the description, which are by way of example and not of limitation, but only in accordance with the scope of the appended claims.

I claim:

1. A back brush comprising a plurality of brush elements having bristles on all sides thereof, two clamps for joining the said brush elements at their ends, each clamp comprising a metal strip bent to form a fold and also wings adjacent to the fold and to each other, an end of two of the brush elements being retained in the fold of each clamp so that the said two brush elements project from the clamps in opposite directions from each other, said clamps each having a hole in the edge of the fold to receive the end of a third one of said brush elements, the wings being pressed together to hold an end of the said third brush element therebetween, said wings being directed away from said brush elements, one end of each

brush element being inserted into each clamp, and two flexible straps, each of said straps having a hole spaced from the end thereof through which the said third brush element passes, each of said clamps having one of said straps folded thereover and fastened so as to form a loop over the clamp to substantially cover said clamp.

2. A back brush comprising a plurality of brush elements having bristles on all sides thereof, two clamps for joining the said brush elements at their ends, each clamp comprising a metal strip bent to form a fold and also wings adjacent to the fold and to each other, an end of two of the brush elements being retained in the fold of each clamp so that the said two brush elements project from the clamp in opposite directions from each other, said clamps each having a hole in the edge of the fold to receive the end of a third one of said brush elements, the wings being pressed together to hold an end of the said third brush element therebetween, said wings being directed away from said brush elements, one end of each

brush element being inserted into each clamp, and two flexible straps, each of said clamps having one of said straps folded thereover with one of said split tabs disposed on each side of said third element, said tabs being fastened to the straps so as to form a loop to substantially cover said clamps.
